UNITED STATES PATENT OFFICE.

WALTER GRUPKA, OF DETROIT, MICHIGAN.

TOY PISTOL.

Application filed December 6, 1923. Serial No. 679,034.

To all whom it may concern:

Be it known that I, WALTER GRUPKA, a citizen of Poland, residing at Detroit, in the county of Wayne and State of Michigan, have invented certain new and useful Improvements in Toy Pistols, of which the following is a specification, reference being had therein to the accompanying drawings.

This invention relates to a toy pistol and 10 has special reference to that class of pistols or projecting devices by which pellets or projectiles may be forcibly projected or discharged, one at a time, the pellets or projectiles being retained in a magazine and automatically fed from the magazine to a projector which is manually retracted, held in a cocked position by trigger mechanism, and adapted to be released so that the expansive force of a spring will cause the projector to 20 discharge a pellet or projectile placed therein.

My invention aims to provide a toy pistol of the above class which is made mainly of sheet metal cut, stamped, and fashioned to 25 form a light-weight, durable and compact pistol having somewhat the appearance of a well known type of magazine fire arm.

My invention further aims to provide a magazine pistol with a novel projector and 30 means actuated thereby for depositing a projectile in the projector and retaining it therein while the projector is retracted or placed in a cocked position preparatory to discharging the projectile.

The construction entering into my toy pistol will be hereinafter described and then claimed, and reference will now be had to the drawings, wherein—

Figure 1 is a longitudinal sectional view 40 of the toy pistol showing the projector thereof as having been placed in a cocked position by a pivoted handle of the piston;

Fig. 2 is a similar view showing the projector released and reloaded;

Fig. 3 is a horizontal sectional view of the pistol with the projector in a released position;

Fig. 4 is a view of the front end of the pistol showing a section line I—I on which 50 Fig. 1 is taken;

Fig. 5 is a view of the rear end of the pistol with the handle partly broken away;

Fig. 6 is an enlarged cross sectional view 55 of the pistol taken on the line VI—VI of Fig. 1;

Fig. 7 is a perspective view of a detached tractor, and

Fig. 8 is a perspective view of a shiftable retaining member carried by the projector, which is shown in dash lines.

In the drawings, the reference numeral 1 denotes a barrel preferably formed of two semi-cylindrical members placed edge to edge and suitably connected together by solder, spot welding or any other means. The 60 barrel 1 has its semi-cylindrical members formed on the lower side of the barrel to provide a longitudinal barrel portion 2, and the rear ends of the barrel members have the side and bottom walls thereof cut away 65 to receive the cheek pieces 3 of a pivoted cocking handle 4, which is also preferably made of two parts placed edge to edge and riveted or otherwise connected together, for instance as at 5. The handle 4 is pivotally 70 mounted, by a transverse pin or rivet 6 between depending lugs 7 at the rear end of the barrel channel portion 2.

Concentric of the barrel 1 is a cylindrical magazine 8 having its front end abutting in-turned lugs 9 at the front end of the barrel 1 and the rear end of the magazine abuts in-turned lugs 10 at the rear end of a barrel. See Figs. 4 and 5. The magazine is adapted for holding a large number of pellets or projectiles 11 which are fed towards the forward end of the magazine by a follower 12 attached to the forward end of a coiled spring 13 within the rear end of the magazine, said coil spring abutting a 80 breech piece 14 having a stem 15 in the magazine, which stem has opposed pins 16 adapted to engage in bayonet shaped slots 17 provided therefor in the walls of the magazine 8. By partially rotating the breech piece 14 it may be removed and the spring 13 and the follower 12 withdrawn, thus permitting of the magazine being loaded with pellets or projectiles. The 85 cheek pieces 3 of the handle 4 provide clearance for the breech piece as best shown in Figs. 1 and 5.

In the forward end of the magazine 8 is an end plate or abutment 18 against the in-turned lugs 9 and retained against said lugs 105 by the expansive force of a coiled spring 19 bearing against a release member 20 slidably in the magazine and adapted to be automatically actuated to release the pellets or projectiles 11, one at a time, through an aper-

ture 21 in the lower side of the magazine. The release member 20 has side arms 22 projecting from slots 23 in the forward end of the magazine 8 and these arms are adapted to be engaged and shifted to move the release member 20, against the action of the spring 19, so that a projectile may drop through the aperture 21.

Slidable on the magazine 8 is a projector 10 24 adapted to be shifted towards the forward end of the channel by the expansive force of a coiled spring 25 encircling the magazine 8 between the projector 24 and the inturned lugs 10 at the rear end of the 15 barrel.

Diametrically opposed outer walls of the projector 24 are provided with studs 26 and connected thereto are rearwardly extending rods 27 which have rear hook shaped 20 ends 28 in loose engagement with eyes 29 on the inner walls of the cheek pieces 3 of the handle 4. The manner of articulating the projector 24 and the handle 4 is such that the pivoted handle may have its 25 lower end swung upwardly under the barrel to cause its upper end to pull rearwardly on the rods 27 and retract the projector 24 and thereby place the spring 25 under compression. After this has been accomplished the pivoted cocking handle 4 may be swung to its normal position with the eyelets 29 sliding on the rods 27.

The projector 24 is formed with a channel chamber 30 which extends into the 35 channel 2 of the barrel 1 and the front end of the chamber 30 is open while the rear end thereof is closed by a wall 31 having a depending lip 32 adapted to be engaged by a resilient detent 33 placed in the slot 34 and attached to the bottom channel wall of the barrel. The detent 33 is adapted to be retracted, to release the projector 24 from a cocked position, by a trigger 35 pivotally mounted in the slot 34 by a transverse pin 36 carried by the channel 40 2 of the barrel 1. The trigger 35 has a forked end 37 normally engaging the end of the detent 33 so that said trigger may be pulled to retract the detent, release the projector 24, and permit the expansive force of the spring 25 to shift the projector forwardly with sufficient impetus to discharge the pellet or projectile placed in the chamber 30, the pellet or projectile passing out 45 of the channel 2 of the barrel 1.

Slidably mounted on the projector 24 is a retaining member 38 having inturned lugs 39 and 40, and a resilient finger 41. The inturned lugs 39 are adapted to engage the end wall 31 of the projector 24 and the inturned lugs 40 are adapted to slide in 50 grooves 42 provided therefor in the inner wall of the projector 24. The retaining member 38 has a limited movement relative to the projector and its skeleton con-

struction provides clearance for the projector lip 32 and the detent 33. The finger 41 is adapted to extend through a side opening 43 of the channel chamber 30 and a wall of the opening 43 is beveled, as at 44, 70 so as to cause retraction of the finger 41 when the projector 24 is shifted forwardly to discharge a projectile from the chamber 30.

Considering the operation of the toy pistol and assuming that the projector 24 is in a cocked position, as shown in Fig. 1, finger pressure on the trigger 35 causes the detent 33 to release the projector 24. As the projector moves forwardly to discharge 75 the projectile from the chamber 30, the projector engages the protruding ends of the arms 22 and causes the release member 20 to be moved forwardly and release a projectile which drops through the aperture 80 21 into the chamber 30 which now has its rear end in proximity to the aperture 21, as shown in Fig. 2.

When the projector 24 moved forwardly it carried with it the retaining member 38, 90 but the impetus of the projector was such as to cause it to move in advance of the retaining member and force the resilient finger 41 outwardly, by virtue of the beveled wall 44, thus providing clearance for forward movement of the projectile. With the projectile discharged and the projector reaching the limit of its forward movement the retaining member 38 and the projector 24 are brought into such relation that the 100 finger 41 projects through the opening 43, as best shown in Fig. 6 and cooperates with the wall 31 in forming a compartment in the chamber 30 to receive a pellet or projectile from the aperture 21. Now, when 105 the projector 24 is retracted by the handle 4 such retraction or downward tilting of the pistol does not cause free movement of the projectile out of the chamber 30. In other words the projectile is temporarily 110 retained in the rear end of the projector until the pistol trigger 35 is again actuated.

Since the pistol parts are preferably made of pressed sheet metal the barrel and handle may have a configuration imparted 115 thereto in imitation of similar parts of a fire arm and it is obvious that all of the sheet metal parts may be quickly assembled, the magazine readily loaded, and the pistol used by juveniles for target practice or 120 other purposes.

One embodiment of my invention has been illustrated, but it is to be understood that the structural elements are susceptible to such variations and modifications as fall 125 within the scope of the appended claims.

What I claim is:—

1. In a toy pistol, a barrel, a magazine in said barrel adapted for holding projectiles, a spring actuated projector on said maga- 130

zine adapted to receive projectiles one at a time from said magazine, a pivoted cocking handle carried by said barrel and adapted for retracting said projector, and a trigger mechanism adapted for holding said projector retracted until manually released.

5 2. A toy pistol as called for in claim 1, and a projectile release member in said magazine adapted to be actuated by said projector to 10 release a projectile for said projector.

15 3. A toy pistol as called for in claim 1, and a spring pressed release member in said magazine having arms extending into said barrel to be engaged by said projector and shifted thereby to release a projectile for 20 said projector.

25 4. A toy pistol as called for in claim 1, and a shiftable retaining member on said projector and adapted to retain a projectile therein during retraction of said projector.

30 5. A toy pistol comprising a barrel, an apertured magazine in said barrel, a projector slidable in said barrel and adapted to receive a projectile from the aperture of said magazine, a release member in said magazine at the aperture thereof adapted to be actuated by said projector to release a projectile to drop through the magazine aperture into said projector, means about said magazine adapted to actuate said projector, and a trigger mechanism adapted for holding said projector in a retracted position.

35 6. A toy pistol as called for in claim 5,

and a spring pressed follower in said magazine adapted to feed projectiles towards said release member.

40 7. A toy pistol as called for in claim 5 and a pivoted handle carried by said barrel adapted for retracting said projector for engagement by said trigger mechanism.

45 8. A toy pistol as called for in claim 5, and a retaining member shiftable on said projector and adapted to retain a projectile in said projector during retraction thereof.

50 9. A toy pistol comprising a barrel, a magazine therein, a projector slidable in said barrel on said magazine and adapted to receive a projectile therefrom, a pivot handle carried by said barrel connected to said projector so as to permit retraction of said projector by said handle and free forward movement of said projector independent of said handle, a spring in said barrel adapted to actuate said projector for the discharge of a projectile, and a trigger mechanism adapted for holding said projector temporarily retracted.

55 10. A toy pistol as called for in claim 9, and means adapted for transferring projectiles from said magazine to said projector.

60 In testimony whereof I affix my signature in presence of two witnesses.
